UNITED STATES PATENT OFFICE.

ARTHUR O. AUSTIN, OF BARBERTON, OHIO, ASSIGNOR, BY MESNE ASSIGNMENTS, TO THE OHIO BRASS COMPANY, OF MANSFIELD, OHIO, A CORPORATION OF NEW JERSEY.

PROCESS OF MANUFACTURING INSULATOR PINS.

Application filed March 1, 1923. Serial No. 621,966.

This invention relates to supports for electrical insulators having a pin on which the insulator is mounted and means for securing the pin to a cross arm or other supporting member. The invention has for its object the provision of an economical and simple method of manufacturing insulator pins which may be easily assembled in place on their supports and which are efficient in operation both from a mechanical and an electrical viewpoint.

The invention also contemplates simplification and improvement of the pin itself so as to facilitate the process of manufacture and provide a pin of maximum efficiency. The invention is exemplified in the combination and arrangement of parts shown in the accompanying drawings and described in the following specification and it is more particularly pointed out in the appended claims.

In the drawings

Fig. 1 is an elevation of one form of insulator pin manufactured according to the present invention.

Fig. 2 shows a slightly modified form of base member.

Fig. 3 illustrates one step of the process of manufacturing the base member.

Fig. 4 illustrates another step in the process.

Figs. 5 and 6 illustrate two steps of the process as performed with slightly different tools from those illustrated in Figs. 3 and 4.

Fig. 7 shows another form of tool that may be used.

Fig. 8 is a section of the base member after punching and before the final finishing operation.

Fig. 9 is a top plan view of another form of base member.

Fig. 10 is a vertical section of the base member shown in Fig. 9 and illustrates the finishing operation therefor.

Fig. 11 is a section on line 11—11 of Fig. 10.

Fig. 12 is a top plan of another form of base member.

Fig. 13 is a vertical section of the member shown in Fig. 12 and illustrates the finishing operation therefor.

As shown in Fig. 1, the numeral 10 designates the body portion of an insulator pin which may be forged or otherwise formed of iron or steel and is preferably galvanized or coated with other suitable protecting ma-

terial. A thimble of lead or other similar material is formed on the upper end of the pin for the purpose of providing a suitable connection with the insulator.

In order to support the pin upon the cross arm it is desirable to have a base member 12 having a considerable bearing surface 13 to rest upon the upper face of the support. It is impractical from a manufacturing standpoint to form this supporting flange integrally with the main body of the pin 10 for the reason that such a method of manufacture would either require the cutting away of a very great amount of metal to reduce the other parts to their proper size or else the expansion by upsetting or other processes of the portion of the metal to form the flange. Both of these methods of manufacture are difficult and expensive. Where a separate base is provided it is desirable that the strength of the pin shall not be reduced at the point where it enters the support, for this is the portion of the pin subjected to the greatest bending moments. It is also desirable that the parts may be readily assembled and easily attached to the support and that a firm connection shall be established between the pin and base member so that they will act substantially as one piece both as to rotary and laterally acting forces. It has been found that a plain taper 14 in the base member 12 which fits a corresponding taper on the pin is well adapted to secure these results. This permits the base member to reinforce the portion of the pin where it is reduced to pass thru the cross arm and also insures a tight fit between the base and pin, since the pin is drawn tightly into the taper by the nut 15 threaded to the pin beneath the cross arm. The perforation thru the base 12 is preferably provided with a straight portion 16 at the bottom thereof to insure proper bearing of the tapered surfaces on the pin and base. When the two fitting tapers are drawn tightly together the friction between the surfaces will resist relative rotation of the pin and base and will cause the two to act substantially as one piece.

Where it is desired to hold the pin against rotation on the cross arm while screwing the insulator on the pin the base may be provided with teeth or projections 17 as shown in Fig. 2 of the drawing. In that figure the supporting base is curved as shown at 18 to fit the upper curved

surface of the rounded cross arm. It will be understood that the teeth 17 may be formed on a flat base such as that shown in Fig. 1 as well as upon a curved supporting surface illustrated in Fig. 2.

In manufacturing the base member 12, it has been found impractical to accurately form the perforation for receiving the pin by the ordinary forging process for the reason that it is difficult to maintain the forging tools sufficiently accurate to provide an accurate fit for the pin and base. Forging deep recesses is also a difficult operation. To overcome these difficulties, according to the present invention the base member 12 is first forged into a shape similar to that illustrated in Figs. 3 and 5 in which the central perforation is formed part way thru the base from both of the opposite sides. This avoids the necessity of forming excessively deep recesses by the forging process and at the same time makes perforation sufficiently deep that the remaining metal 17 may be severed from the base member by drilling or punching to complete the perforation. In finishing the base from the forging as shown in Fig. 5 the metal 17' may first be drilled from the center of the forging and the tapered opening may then be completed by means of a reamer of proper size and taper. Another method of completing the base is to insert a cylindrical punch into the upper tapered opening as illustrated in Fig. 5 and force the material 17 downwardly completing the perforation, the forging being held by a suitable supporting die 18 (Fig. 3) having a stripper 19 connected therewith. After the punching operation a tapered drift tool 20, Fig. 7, is forced into the tapered opening, the drift tool 20 being of proper size and taper to correspond to the tapered portion of the pin 10. The finishing operations may be performed with the metal either hot or cold. A single tool may be employed as illustrated in Figs. 3 and 4 for both punching and shaping the interior of the perforation, but if separate tools are used it is found that in some cases less difficulty will be experienced in maintaining the tools in proper condition. The drift tool may in some cases be provided with a guiding boss or pilot 21, as shown in Fig. 7, or this guide may be omitted as shown in Fig. 6. After punching, the base member will have the form illustrated in Fig. 8 and the metal inside the broken lines 22 will be forced back by the finishing tool to give the correct taper shown by these lines. In Figs. 9, 10 and 11 there is shown a base member having a tapered socket with angular sectional shape. This can be finished from the form of forging shown in Figs. 3 and 5 by a punch like that shown at 22', Fig. 10. The base may be provided with ears 23 to hold it from turning on the base while an insulator is screwed to the top of the pin,

which will of course be provided with an angular-taper portion to fit the socket in the base member. The base member is also provided with an outer angular portion 27, upon which a wrench may be fitted to hold the pin 70 while the insulator is screwed on.

In the form of base shown in Figs. 12 and 13, the base flange is provided with openings 24 through which bolts or cap screws may be passed for securing it to its support. In this form the underside of the base is recessed at 25 to receive a nut 26 for holding the pin to the base. This form is especially valuable for use with bus bars and other installations where the base is anchored on the support. 80

I claim:

1. The process of manufacturing an insulator pin wherein a pin body and base are separately formed the base being shaped and partially perforated by forging after which the perforation is completed by a severing operation the interior of said perforation being given a predetermined taper to correspond to a tapered portion of said pin body the shape of said tapered perforation being produced by a tool of corresponding shape and size which is forced into said perforation. 90

2. The process of manufacturing an insulator pin wherein a separate base member is first shaped by forging and a perforation formed part way therethru after which the perforation is completed by punching and the interior thereof is given a tapered formation to fit a tapered portion of a pin to be supported thereby said tapered formation being imparted to said perforation by a drift tool forced into said perforation. 100

3. The process of manufacturing an insulator support wherein a pin body and a base member are separately formed said base member being roughly formed by forging and being finished to provide a perforation therethru, having a tapered portion of predetermined size and shape to correspond to 110 a similar tapered portion on said pin body, the pin body being inserted in said base member and secured in place in said base member by an attaching means arranged to draw the tapered portion of said pin body and base 115 member tightly together.

4. The process of manufacturing an insulator support comprising the steps of forming a pin body having portions of different diameters connected by an intermediate tapered portion, separately forming a base member to support said pin body and having a socket to fit said intermediate tapered portion, and forming the socket in said base member in separate steps including a combined punching and shaping operation. 120

In testimony whereof I have signed my name to this specification on this 24th day of February, A. D. 1923.

ARTHUR O. AUSTIN.
